UNITED STATES PATENT OFFICE.

JUSTUS C. GOOSMANN, OF CHICAGO, ILLINOIS.

VALVE.

Application filed November 25, 1921. Serial No. 517,732.

To all whom it may concern:

Be it known that I, JUSTUS C. GOOSMANN, citizen of the United States, residing at Chicago, in the county of Cook and State of Illinois, have invented new and useful Improvements in Valves; and I do hereby declare that the following is a full, clear, and exact description of the invention, which will enable others skilled in the art to which it appertains to make and use the same.

This invention relates to improvements in valves. It pertains more particularly, however, to a valve of the pressure-relation regulating type.

One of the objects of the invention is the provision of an adjustable seat for the closure of a valve, especially of the type named, whereby the necessary free area for the flow of a gas may be obtained without disturbing the normal position of certain diaphragms carrying such closure.

Another object is the provision of an adjustable seat for the closure of a valve employing diaphragms carrying said closure whereby an exact disposal of said seat with respect to the closure is possible.

Still another object is to combine an adjustable seat with the closure of a valve of the type forming the subject of my copending patent application No. 364,840 filed March 10, 1920 wherein, by the use of such adjustable seat, deposits or accumulations of sediment, scale from the pipe system, small chips and particles of dirt which may obstruct the free area of the valve passages will be readily discharged without disturbing the normal position of the diaphragms.

In the appended drawing forming part of this application,

Figure 1 is a longitudinal section elevation of a pressure-relation regulating valve showing the adjustable valve seat of my invention applied thereto;

Figure 2 is a similar view of details of part of what is shown in Figure 1, produced on a larger scale and

Figure 3 is an elevation of an adjustable valve-seat seat shown in Figure 1.

The first two figures illustrate the type of valve of my former application referred to and since described in that application its details will not be explained herein except in so far as may be required to show their relationship in connection with the present invention.

In a valve for refrigerating systems wherein a gas is employed, the adjustment between the closure and usual fixed valve-seat must be very carefully made and especially in a valve of the type that employs diaphragms carrying the closure and having unequal areas which are to be separately affected by gas pressures.

When a valve-seat is fixed or forms an integral part of the body of the valve it is quite difficult, even with careful machining, to obtain the proper or exact relation between it and the closure when the body parts are bolted together, since either the seat will

have such a position relatively to the said closure that it will engage said closure and therethrough stress the diaphragms from their normal positions in one direction, which would cause them to be more or less unresponsive to the pressure of gas, or the seat may be so far away from the closure as to make the control of the refrigerant difficult, requiring the adjustment of the said closure toward the seat by outside means in the other direction which in turn would, in some cases, again deflect the diaphragms from their normal or proper working positions and make them more or less unresponsive, and sufficient flexibility would be lacking to permit free action and allow accumulation of foreign matter to be discharged.

In view of the difficulties usually encountered, it is my purpose to furnish an adjustable seat by which the proper working conditions may be made possible.

In the drawing 1 designates the body of the valve provided with a recess 2, which in the assembled valve is a closed cavity, as will be understood later, communicating with which is a passage 3 for the introduction of a high pressure gas.

Communicating with the bottom of the recess is a threaded bore 4 connecting said recess with a cavity 5 in said body. In the lower portion of the body centrally in line with the bore 4 is a cavity 6.

Having threaded engagement with the bore 4 is a tubular member 7 whose upper end terminates in a conically formed valve-seat 8. Said member has a transverse bore 9 communicating with a passage 10 in the body as the outlet for low pressure gas.

The vertical passage 11 of the member 7 communicates with the cavity 5 for a purpose to be described.

A stem 12 is part of the member 7 and extends into and through the cavity 6 of the body, and threaded into the latter is a packing nut 13 which confines and compresses a packing 14 around said stem.

Preferably a cap or bonnet 13' encloses the protruding squared end of the stem and has threaded engagement with the nut 13.

Mounted upon the body 1 and secured thereto by means of a screw 15, for example, is a bonnet 16 and an intermediate section 17, the latter having interposed between it and the recess 2 of said body a diaphragm 18. Between the bonnet and said intermediate section 17 is a second diaphragm 19, larger than the other, while 20 is the closure carried by the two diaphragms adapted to work in conjunction with the seat 8 to control the refrigerant entering through the passage 3 and leaving through the passage 10. The arrangement of the closure and diaphragms is substantially the same as my former application referred to, and, being well known for that reason, requires no further elucidation.

As in the device of said application the high and low pressure gases are designed to reach the small and large diaphragms, respectively, for the operation of the closure.

If the diaphragms, which are fixed with respect to the closure 20, are flexed in one direction by mechanical means acting on the closure in order to carry said closure to the proper working position with respect to the valve-seat 8, or the seat if too high engages the closure and flexes said diaphragms in the other direction, these members cannot properly function.

The provision of the adjustable seat permits any desired relation thereof with respect to the closure without the diaphragms being affected in any way. Therefore, said diaphragms retain at all times the true working form and consequently are readily influenced by pressure of the refrigerant, yielding exact results.

The seat adjustment provides for the necessary free area for the flow of the refrigerant without disturbing the normal position of the diaphragms. Said seat may be moved farther away from and closer to the closure by turning it by means of the stem 12, as normally required, and can be fixed in proper position by any good means if found necessary. Any change in the normal and adjusted condition of the refrigerating system which reacts upon the valve will be properly readjusted by the closure as it moves with the influenced diaphragms, until normal and original conditions are re-established. For example, if an accumulation of sediment, scale from the pipe system, small chips and particles of dirt obstruct the free area of the passage beneath the closure, the low pressure will

drop while the high pressure will correspondingly increase and act upon the small diaphragm 18 deflecting it upwardly until the increase in the free area of valve passage becomes large enough to permit the accumulations mentioned to pass and blow through. As this occurs the closure will resume its original and normal position. The ability to obtain an exact relation between the seat and closure is of no little importance for the reasons stated, as is well known to those familiar with and having to do with valves of this type as used with refrigerating systems particularly.

The range of adjustment of the member 7 upon its threads is never such as to materially change the effective area of the low pressure passages 9, 10. The accumulations when blown through are trapped in the cavity 5 after having passed down through the bore 11, this being likewise true of any oil that may pass through the valve. However, this provision for catching the accumulations and oil may not be resorted to, the adjustability of the seat being the point of importance to be kept in mind.

Preferably a gasket 21 is let into the body 1 at the bottom of the recess 2. This closely hugs the threads of the member 7, which it encloses, so that the pressure of the gas and small accumulations of oil will closely seal the threads against leakage of gas pressure therealong.

I claim:

1. The combination with a valve including a passage extending through the body of the valve, a closure, and diaphragms carrying said closure, of a valve-seat in said passage for receiving the closure adjustable in the said body in the direction of said closure. 100

2. The combination with a valve including a passage extending through the body thereof and a closure for said passage, of a tubular valve-seat seated in said passage opposite the closure and adjustable therein in the direction of said closure a discharge passage communicating with the bore of said seat between its ends, and a collection chamber connecting with said bore at the opposite end thereof from the closure. 110

3. The combination with a valve including a passage extending through the body thereof, and a closure for said passage, of a tubular member including a valve-seat disposed in said passage opposite the closure and adjustable therein in the direction of said closure, and a gasket seated in the valve body enclosing the member. 120

4. A valve of the character described, comprising a casing provided with a high pressure chamber and a low pressure chamber, diaphragms of different areas forming one wall of each of said chambers, a valve carried and controlled by said diaphragms, a hollow valve seat adjustably mounted in the 125

casing and extending into said high pressure chamber, and means operable from outside the casing for adjusting said valve seat.

5. A valve of the character described, comprising a casing provided with a high pressure chamber and a low pressure chamber, diaphragms of different areas forming a portion of said chambers respectively, a valve carried and controlled by said diaphragms, a collection chamber, a tubular

valve seat adjustably threaded into said casing in position to cooperate with said valve, said seat opening at one end into the high pressure chamber and at its other end into said collection chamber, and a discharge 15 duct communicating with said valve seat intermediate its ends.

In testimony whereof I affix my signature.

JUSTUS C. GOOSMANN.
